UNITED STATES PATENT OFFICE.

WILLIAM L. DECKER, OF GRASMERE, NEW YORK, ASSIGNOR TO PLATT AND DECKER, OF NEW YORK, N. Y., A FIRM.

OIL AND WATER RETORT AND BURNER.

SPECIFICATION forming part of Letters Patent No. 783,938, dated February 28, 1905.

Application filed April 27, 1904. Serial No. 205,059.

To all whom it may concern:

Be it known that I, WILLIAM L. DECKER, a citizen of the United States, residing at Grasmere, Staten Island, in the county of Richmond and State of New York, have invented certain new and useful Improvements in Oil and Water Retorts and Burners; and I do hereby declare the following to be a full, clear, and exact description of the invention, such as will enable others skilled in the art to which it appertains to make and use the same.

My invention relates to a gas-generating mechanism; and it consists in a new construction and arrangement of parts for vaporizing oil and water, mixing and superheating the vapors. The important features are the generator composed of an outer shell, a water-supply pipe thereto, an inner shell arranged within the outer shell, an oil-pipe to the inner shell, a burner arranged below the outer shell, and a connecting-pipe between the generator and the burner to conduct the vapor to the latter. Both shells are filled or packed with any suitable fibrous, granular, or porous material, so that extra heating-surface is provided and the liquids percolating therethrough are broken up so as to be easily vaporized and mixed before they pass into the burner. By this mechanism the oil and water are continuously vaporized, the vapors thoroughly mixed, so that when burned an intense heat is generated with great economy of fuel.

My invention will be understood by reference to the drawings herewith, in which the reference-numerals of the specification indicate the same parts in all the figures.

Figure I is a longitudinal section of a stove provided with my invention with portions of the generator in section and portions broken away. Fig. II is an end elevation thereof. Fig. III is a vertical cross-section of Fig. I. Fig. IV shows a modification of the inner shell in the form of a trough having an elongated opening toward its outer end.

In the figures, 1 indicates the stove or heater of any desirable construction in which the grate is not necessary, but where provided with a grate 2, as in case of an old stove or heater, it need not be disturbed, but the gen-

erator may be suitably arranged with reference thereto, commonly below it. This generator consists of an outer shell of any suitable size, shape, and material, here shown as a piece 4 of iron pipe, having the ends closed by caps 5, into the inner of which are tapped the water and oil inlets 7 8, which may extend through any openings in the side of the stove or through holes specially drilled to receive them and by which the generator is supported at its inner end. In the outer shell is arranged the inner or oil shell 10, also of any suitable size, shape, and material, and here shown as a piece of smaller pipe with its ends closed by caps 11 11, into the inner end of which is tapped the oil-inlet 8. To said inlets by unions 13 13 are respectively connected the water-supply pipe 15, provided with suitable valve 16, and the oil-supply pipe 17, provided with suitable valve 18, said pipes conducting the respective liquids from any suitable source of supply, such sources being arranged above and fed by gravity or below and at any distance with a feed under pressure. The interior of both shells is filled and packed with any suitable porous, granular, or fibrous refractory material, leaving interstices through which the liquids percolate, such as iron or steel chips or filings, coarse sand, asbestos, &c. At its outer end the outer shell is provided with a perforated shield or strainer 20 to prevent the packing from entering the connecting-pipe 21, communicating with the burner or burners 22, provided with vapor-holes in its top and arranged longitudinally beneath the generator or any other suitable form of burner, such as the tubular burner, here shown arranged in any convenient situation to heat the generator.

23 is the supporting-leg for the burner, by which also the generator is supported at its outer end.

In the generator the liquids are thoroughly broken up, so as to be more easily vaporized, and the oil-vapor passing out through the holes in the top of the inner shell near its inner end is thoroughly mixed with the requisite quantity of steam generated at the same time in the outer shell, whence the mixed vapor passes into the burner, where it burns, generating a high de-

gree of heat, so that the generator is quickly and highly heated, and the flame fills the fire-box and passes up through the grate, where it is preferably checked by perforated baffle-plate 5 30, which insures the consuming of all the gases. In place of the baffle-plate might be substituted a filling or layer of broken fire-brick, steel shavings, or other suitable material. In this manner a high degree of heat is generated 10 and all utilized to heat the stove; but, if desired, the gas may be drawn off through a pipe 33, provided with valve 32, desirably extending over burner 22 to superheat the gas for use outside of the stove at any convenient 15 distance and for any suitable purpose, sufficient gas being permitted to pass to the burner to keep up the heat and the generation.

The inner shell is preferably arranged above the middle of the outer shell, as the oil vaporizes much faster than the water. The generator may be initially heated up to begin the process in any suitable way, as by means of the pan 31, arranged in the bottom of the stove, in which a little oil may be ignited. As 20 25 soon as the generator has become well heated up the supply of oil and water may be reduced, and by reducing the supply very low the gases are all consumed low down in the stove and the baffle-plate may be used as a broiler, 30 toaster, &c. I have shown a desirable form of mechanism, but do not limit myself thereto, as the form and arrangement may be varied without departing from the spirit of my invention.

35 My invention is particularly adapted for domestic use and may be used with any construction of stove even not specially devised therefor and may be arranged in an old stove, range, or heater of substantially any construction. It may be also adapted to steam-generators and used in the arts as for the melting of metals, &c., and provides a high degree of heat, burning, preferably, with a blue flame with a great economy of fuel and is safe and 40 45 clean. It produces a superior water-gas for all purposes, heating, lighting, development of power, use in gas-engines, &c.

Having thus described my invention, what I claim as new, and desire to secure by Letters 50 Patent, is—

1. In a gas generator and heater, the combination with a heater of any suitable construction, of an elongated outer shell arranged substantially horizontally within the heater, a 55 smaller elongated inner shell arranged within and in the upper portion of the outer shell and communicating therewith, said shells having their inlet ends arranged adjacent to the heater-casing, of a water-supply pipe passing through 60 the casing to communicate immediately with the outer shell, an oil-supply pipe passing through the casing and communicating immediately with the inner shell, means to subdivide the liquids immediately on their admission to 65 their respective shells, valves in said supply-

pipes, and a burner arranged beneath the outer shell.

2. In a gas-generator, the combination with a large outer shell, of a trough-like inner shell having an enlarged top opening arranged with-in and near the top of the outer shell, to leave a large mixing-space within the outer shell and without the inner shell, of a water-supply pipe to the outer shell, an oil-supply pipe to the inner shell, a burner beneath the outer 75 shell and a vapor-pipe from the outer shell.

3. In a gas generator and heater, the combination with a heater of any suitable construction, of a cylindrical outer shell arranged substantially horizontally within the heater, a substantially cylindrical inner shell arranged within and in the upper portion of the outer shell and communicating therewith, said shells having their inlet ends arranged adjacent to the heater-casing, of a water-supply pipe passing through the casing to communicate immediately with the outer shell, an oil-supply pipe passing through the casing and communicating immediately with the inner shell, means to subdivide the liquids immediately on their 80 admission to their respective shells, valves in said supply-pipes, a tubular burner arranged beneath the outer shell and a connecting-pipe from the outlet end of the outer shell to the burner. 85

4. In a gas generator and heater, the combination with the outer shell, of a small inner shell arranged within and in the upper portion of the outer shell, to leave a large mixing-space around the inner shell, water and oil 90 supply pipes connected, respectively, to the outer shell and to the inner shell, a tubular burner arranged beneath the outer shell, a gas-pipe from the outer shell to the burner, a gas draw-off pipe from the outer shell extending 100 over the burner and substantially parallel therewith, and a filling of porous material within the shells to break up the liquids immediately on their admission to their respective shells. 105

5. In a heater, the combination with a cylindrical outer shell arranged within the heater-body, of a water-supply pipe connected to said shell at its inlet end, a cylindrical trough-like inner shell having an elongated top opening 110 arranged within the outer shell, an oil-supply pipe connected to the inner shell at its corresponding inlet end, valves in said pipes, a tubular burner arranged beneath the outer shell, a connecting-pipe from the outlet end of the 115 outer shell to the burner, a filling of porous material in both shells, and a strainer in the outlet end of the outer shell to retain the porous material. 120

In testimony whereof I affix my signature 125 in presence of two witnesses.

WILLIAM L. DECKER.
